UNITED STATES PATENT OFFICE.

ALEXANDER M. ALEXANDER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING-MACHINE.

1,318,343.

Specification of Letters Patent.

Patented Oct. 14, 1919.

Application filed July 1, 1911. Serial No. 636,494.

To all whom it may concern:

Be it known that I, ALEXANDER M. ALEXANDER, a citizen of the United States, residing at Beverly, in the county of Essex 5 and State of Massachusetts, have invented certain new and useful Improvements in Skiving-Machines; and I do hereby declare the following to be a full, clear, and exact description of the invention, such as will enable others skilled in the art to which it 10 pertains, to make and use the same.

The present invention relates to leather skiving machines and more particularly to machines which comprise a rotary cylindrical skiving knife, a presser foot and a feed roll arranged to hold the leather in position and feed it to the knife.

Machines of this class are employed, among other things, for beveling or skiving 20 the edges of thin sheets of leather and it is desirable that they may be adjusted to vary the angle of the bevel with precision and rapidity in order to accommodate a variety of kinds of work. This variation in the angle of the bevel is generally secured by varying 25 the angular relation between the working face of the presser foot and the cutting portion of the knife edge, but in order to obtain the correct relation between the 30 presser foot and knife it is generally necessary to provide several adjustments of the presser foot and in some cases also an adjustment of the knife. It will thus be obvious to those skilled in the art that if the 35 operator is required to make several adjustments in order to obtain the correct relation between the presser foot and knife considerable time and labor is necessarily lost.

40 The object of the present invention is to enable the angle of the bevel to be accurately determined within reasonable limits and to enable the required angle of bevel to be obtained with the manipulation of only 45 a single adjusting member. With this object in view, one feature of the invention consists in the combination with a cylindrical skiving knife and feed roll of a presser foot having provision for adjustment about 50 an axis inclined to a radius passing through the point at which the axis intersects the cylindrical surface within which the knife edge lies. This surface will for convenience be referred to as the cylindrical sur-

face of the knife edge. Still further features of the invention comprise certain novel features of construction, combinations and arrangements of parts hereinafter described and claimed, the advantages of which will be apparent to those skilled in the art from 55 the following description.

In the accompanying drawings illustrating the preferred form of the invention;

Figure 1 is a detail showing a partial front elevation of the machine and illustrating the several features of the invention in 60 their preferred forms;

Fig. 2 is a top plan view of the presser foot removed from the machine;

Fig. 3 is a detail illustrating a side elevation, partly in section, of the presser foot and the several elements of the machine co-operating therewith;

Fig. 4 is a section taken upon the line 4-4 of Fig. 3, looking in the direction of 75 the arrows; and

Fig. 5 is a detail view showing a cross section of the work and illustrating the action of the knife upon the same.

Certain parts of the machine are similar 80 in construction and mode of operation to the machine shown and described in the co-pending application of Alexander, Serial No. 621,679, filed April 17, 1911, and will be only briefly described herein in consequence 85 thereof.

This machine is provided with a cylindrical skiving knife indicated at 3 which is mounted within a casing 4 and projects upwardly through an opening in the same into 90 a position to act upon the material. The material to be skived is fed to the knife 3 by a positively driven feed roll 5 which is yieldingly supported within the knife and which cooperates with a presser foot 6 95 mounted without the knife and arranged to act as a gage for properly presenting the work to the knife. The periphery of the feed roll and the working face of the presser foot are curved to correspond with the curvature of the knife edge in order that the knife shall make a straight cut. The presser foot 6 is carried by a block 7 slidingly mounted in vertical guideways formed in the end of an overhanging arm 8 and an adjusting mechanism (not shown) is provided 100 for determining the initial vertical position of the presser foot in order to bring 105

it into coöperating relation with the knife edge. The work is guided into an operative position by an adjustable gage 9 which engages with the edge of the material as it is fed to the knife.

When this machine is used for beveling, the working face of the presser foot is positioned eccentrically to the knife edge and in the illustrated embodiment of the invention one edge of the working face is arranged substantially in alignment with the knife edge. When it is desired to form a feather edge upon the material, the edge gage is adjusted into a position in alignment with this edge of the presser foot and when it is desired to have the beveled edge of a substantial thickness, the edge gage is adjusted to a point between the edges of the presser foot. In order to vary the angle of the bevel which is formed upon the work, the eccentricity of the working face of the presser foot is increased or decreased as desired and this is accomplished, without varying the fixed operative relation between the edge of the presser foot and the knife edge, by adjusting the presser foot about an axis which is inclined to a radius passing through the point at which the axis intersects the cylindrical surface of the knife edge. In the simplest and most efficient form of the invention which has as yet been devised, the presser foot is positioned above the front side of the knife and is adjusted about an axis inclined rearwardly to a radius passing through the point of intersection of the axis with the cylindrical surface of the knife edge.

To this end the presser foot 6, as shown clearly in Figs. 1 and 3, is pivotally connected to a supporting member 10 adjustably held in the block 7 in the usual manner and which is provided with laterally projecting ears 12 serving to support a pin 13 in an oblique position upon which the presser foot 6 is journaled. In order to readily adjust the presser foot, an actuating member, indicated generally at 14, extends forwardly from the presser foot and supporting block and is provided with a knurled operating head 15 conveniently accessible to the operator. This actuating member is provided at its rear end with a worm 16 which engages with a worm gear 17 formed upon the rear face of the presser foot so that upon a rotation of the actuating member 14 the presser foot 6 will be adjusted about the pin 13. The actuating member 14 consists of a rod 18 having the worm 16 formed thereon and provided with a head 19 at its opposite end which is arranged to engage with the rear face of the supporting member 10 and retain the actuating member in the proper position. The knurled head 15 is locked to the rod 18 by a pin 20, and a sleeve 21 serves as a bearing

member for the rod and maintains the actuating member in the proper position relative to the block 10. From the above description it will be obvious to those skilled in the art that upon a slight rotation of the actuating member the presser foot will be turned about the pin 13 and the angular relation between the working face of the presser foot and the edge of the knife will be correspondingly varied. It will also be apparent that this turning movement does not disturb the adjustment of the edge of the presser foot, which is positioned in alignment with the knife edge, thus enabling the required adjustment to be obtained with only a single manipulation of the actuating member. Although the adjustment of the presser foot to vary the angle of the bevel produces a slight longitudinal movement of the face of the presser foot with relation to the edge of the skiving knife, the working face of the presser foot is made of a sufficient width to properly bear upon the material at all times and this adjustment consequently does not affect the proper relation between the presser foot and coöperating parts.

Although the present invention has been described in connection with a machine embodying a cylindrical knife and although the several features of the invention are advantageously employed with such a machine, yet it is to be understood that the invention may be embodied in machines employing other styles of skiving knives if so desired.

While it is preferred to employ the specific construction and arrangement of parts shown and described, it is to be understood that this construction and arrangement is not essential except so far as specified in the claims and may be changed or modified without departing from the broader features of the invention.

Having thus described the invention, what is claimed is:—

1. A leather skiving machine having, in combination, a cylindrical knife, a feed roll at one side of the knife, and a presser foot upon the opposite side of the knife having provision for adjustment about an axis inclined to a radius passing through the point at which the axis intersects the cylindrical surface of the knife edge, substantially as described.

2. A leather skiving machine having, in combination, a cylindrical knife, a feed roll at one side of the knife, and a presser foot upon the opposite side of the knife having provision for adjustment about an axis extending obliquely to the plane of the knife edge in order to vary the bevel cut by the knife, substantially as described.

3. A leather skiving machine, having, in combination, a skiving knife, a feed roll at one side of the knife, a presser foot upon

- the opposite side of the knife having a working face with one edge positioned in operative relation to the knife edge, and a single means for varying the angular relation of 5 the working face of the presser foot to the knife edge while maintaining a fixed operative relation between the edge of the presser foot and the knife edge, substantially as described.
- 10 4. A leather skiving machine having, in combination, a cylindrical knife, a feed roll, a presser foot having provision for adjustment about an axis inclined to a radius passing through the point at which the axis 15 intersects the cylindrical surface of the knife edge, a worm gear formed upon the presser foot, and an actuating member having a worm formed thereon and arranged to engage with the worm gear to adjust the 20 presser foot, substantially as described.
5. A leather skiving machine having in combination, a cylindrical knife, a feed roll within the knife, a presser foot above the front side of the knife and having provision 25 for adjustment about an axis inclined rearwardly to a radius passing through the point at which the axis intersects the cylindrical surface of the knife edge, and an actuating member for adjusting the presser 30 foot, substantially as described.
6. A leather skiving machine having, in combination, a cylindrical skiving knife, a feed roll at one side of the knife, and a presser foot upon the opposite side of the
- knife having provision for adjustment about 35 an oblique axis to vary the angle of the bevel cut by the knife, substantially as described.
7. A skiving machine comprising in combination, a knife, a feed roll arranged in proximity to said knife, a normally stationary gage arranged oppositely to said feed roll, means for adjusting said gage toward and from the feed roll, and means for adjusting the gage angularly about a point 40 lying in the operative portion of the gage 45 and adjacent to one end thereof.
8. A skiving machine comprising a cylindrical knife having an edge at one end, a normally stationary gage mounted near said edge and having its surface adjacent to the 50 edge approximately concentric therewith, a slide on which said gage is mounted movable in a plane perpendicular to the axis of the knife, and means for moving said slide, said gage being adjustably mounted on said 55 slide for movement angularly about a point approximately in its operative edge.
9. A gaging means for a skiving machine comprising a normally stationary top gage, means for adjusting said top gage angularly 60 about a point approximately in its operative surface, and means for adjusting the said gage bodily in a direction transverse to its operative surface.
